UNITED STATES PATENT OFFICE.

PACIFIQUE CHÉRAZ, OF WIDNOON, PENNSYLVANIA.

ACETYLENE-GENERATOR.

1,084,787.

Specification of Letters Patent.

Patented Jan. 20, 1914.

Application filed August 2, 1912. Serial No. 712,959.

To all whom it may concern:

Be it known that I, PACIFIQUE CHÉRAZ, a citizen of the United States, residing at Widnoon, in the county of Armstrong, State 5 of Pennsylvania, have invented certain new and useful Improvements in Acetylene-Generators; and I do hereby declare the following to be a full, clear, and exact description of the invention, such as will enable others 10 skilled in the art to which it appertains to make and use the same.

This invention relates to new and useful improvements in lanterns and more particularly to hand lanterns of the acetylene type 15 burning acetylene gas and which are so constructed that they cannot be blown out by the wind and so that the possibility of smoking or danger of fire is reduced to a minimum.

20 With the above and other objects in view, the invention consists of certain other combinations and arrangements of parts as will be hereinafter more fully described, claimed and illustrated in the accompanying drawings, in which:

Figure 1 is a side elevation of my improved lantern. Fig. 2 is a top plan view thereof. Fig. 3 is a central vertical sectional view. Fig. 4 is a horizontal sectional view 30 taken on the line 4—4 of Fig. 3. Fig. 5 is a bottom plan view of the acetylene burner reservoir removed from the base. Fig. 6 is a detail view of a joint connecting the latter parts.

35 Referring to the drawings in detail, my improved carbid or acetylene gas lantern comprises a base or ring support 10 to which the lower extremities of supporting legs 11 are attached at equi-distantly spaced points 40 while the upper ends of the legs are attached to an intermediate supporting band 12 adapted to encircle a cylinder 13. This cylinder 13 in turn serves for the attachment of a main bail 14 having the lower extremities of its side portions bent to form hooks 15 which are pivotally engaged with the cylinder near its top portion. The cylinder is thus swingingly supported by the bail and it will be observed that the bail comprises 45 a single section of wire bent at right angles at two points to form eyes 16 receiving the lower extremities of a relatively circular handle bail 17 which are pivotally connected therethrough to allow swinging movement of 50 the main bail relative thereto. The cylinder is also provided with a reduced collar 18

having an inwardly extended bottom flange 19 adapted to receive and support respectively, the rim portion of a transparent globe 20 which is received between the side 60 portions of the main bail and is held from upward displacement by a cross wire or retaining member 21 having its ends formed with coils 22 slideable on the guide forming side portions of the main bail and held 65 downwardly displaced by coiled springs 23 mounted on said side portions between the connecting portion of the main bail and washer plates 24 connected to the coils 22. It will of course be understood that the 70 springs tend to exert downward pressure on the retaining member to engage the upper end of the globe and thus prevent vertical or lateral displacement thereof.

The lamp further embodies a water tank 75 or reservoir 25 formed at its lower end with an enlarged flanged rim 26 having diametrically oppositely disposed slotted plates 27 formed with outwardly bent or bayonet portions 28 for engagement by similarly disposed pins 29 carried by the cylinder 13 when the latter is engaged within the flange of the rim so that said parts are secured together and the gas generating apparatus is supported by the frame. The tank 25 is 80 formed with a reduced centrally disposed and internally threaded bottom portion 30 receiving the reduced externally threaded neck 31 of a carbid reservoir or holder 32 which is provided with an interposed packing ring 33 rendering the joint air tight to prevent the escape of gas generated in the holder and which escapes through a central vertical supply tube 34 to the burner tip 35. The water tank is provided with a screw 85 cap 36 for supplying water thereto and the feeding of the water to the carbid is regulated by a valve stem 37 carrying a metallic plate 38 and compression valve 39 for closing against a supply tube 40 depending from 90 the bottom of the tank into the carbid holder at one side thereof. It will also be observed that the stem extends through the tube 40 and depends therebeneath to form a drip feed for the water. In order to regulate 95 the supply of the water, the upper end of the stem carries a pinion 41 and a threaded enlargement 42 therebeneath engaged with a threaded extension 43 of the tank so that the valve is moved vertically by means of rotation imparted to a tube-inclosed shaft 44 mounted on one side of the tank and having 100 105 110

a pinion 45 at its upper end in mesh with the pinion 41 and capable of being conveniently rotated by a small lever or crank handle 46 secured to the lower end of the shaft beneath the flanged rim. This last named construction permits convenient control of the burner without removing the globe or frame.

From the foregoing description in connection with the accompanying drawings, it will be seen that besides providing a lantern and frame construction which will prevent the same from blowing out and reduce the liability of smoke and fire, the parts are so assembled as to permit the same to be rigidly connected and readily taken apart for cleaning but still constructed to durably serve the rough usage to which a device of this character is generally put.

I claim:

20 In an acetylene generator, a tank having an upwardly depressed button forming a socket provided with screw threads, a carbide

receptacle having a screw threaded neck fitting in said socket, a gas tube projecting through said tank and communicating with said receptacle, a valve stem parallel with said tube and having a valve controlling a port that establishes communication between said tank and said receptacle, a stub shaft parallel with said stem, a bearing on said tank housing said shaft, meshing gears connecting the upper ends of said shaft and said stem above the top of said tank, and a crank handle fixed to the lower end of said shaft for rotating said shaft in either direction with a resultant actuation of said valve stem by said gears to open or close said valve.

25 In testimony whereof, I affix my signature, in presence of two witnesses.

30 PACIFIQUE CHÉRAZ.
